CARD GAME RECORDING INSTRUMENT

Stephen E. Mucha, Erie, Pa.

Application February 17, 1954, Serial No. 29,072

Term of patent 3½ years

(Cl. D34—13)

FIG. 1

FIG. 2

Fig. 1 is a top plan view of a card game recording instrument, showing my new design; and

Fig. 2 is a side elevational view thereof.

The drawing figures are diagonally lined to indicate transparency.

I claim:

The ornamental design for a card game recording instrument, as shown and described.
